SHAKER CONVEYOR

William W. Sloane, Chicago, Ill., assignor to
 Goodman Manufacturing Company, Chicago,
 Ill., a corporation of Illinois.

Application December 28, 1945, Serial No. 637,645

9 Claims. (Cl. 198—220.)

1

This invention relates to improvements in shaker conveyors, and more particularly relates to improvements in articulated connections for shaker conveyor trough lines arranged to permit lateral movement of one trough of the conveyor with respect to another trough of the conveyor, for conveying material around corners.

The principal object of my invention is to provide a new and improved form of articulated connection for a shaker conveyor trough line, so arranged that the base of the articulated connection may be held in position on an irregular mine bottom and may be bent to substantially conform to the mine bottom without distorting or binding the moving parts of the articulated connection.

An application Serial No. 636,730, filed by Loy D. Hagenbook on December 22, 1945, now Patent No. 2,424,394, discloses a means for holding the base of an articulated connection for a conveyor trough line in position on an uneven bottom, without bending the base of the articulated connection or binding the moving parts mounted thereon. The device of my present invention is somewhat similar to that disclosed in the before-mentioned application of L. D. Hagenbook, but differs therefrom in that the base is jacked down on the mine bottom and may be bent to substantially conform to the uneven mine bottom, by the jacks interposed between the base and the mine roof, and has a plate mounted thereon for restrained vertical movement with respect thereto, which carries the moving parts of the articulated connection so that bending of the base will not bend the plate or affect the parts mounted thereon.

This and other objects of my invention will appear from time to time as the following specification proceeds and with reference to the accompanying drawings wherein:

Figure 1 is a plan view of an articulated connection for a shaker conveyor trough line constructed in accordance with my invention, with certain parts broken away and certain other parts shown in horizontal section in order to more clearly illustrate certain details of my invention;

Figure 2 is a view in side elevation of the swivel shown in Figure 1, with certain parts thereof shown in substantially longitudinal section;

Figure 3 is a transverse sectional view taken substantially along line 3—3 of Figure 1;

Figure 4 is a transverse sectional view taken substantially along line 4—4 of Figure 1;

Figure 5 is an enlarged detail fragmentary plan view showing certain details of the mountings

2

of one of the supporting and guide sheaves for the articulated connection shown in Figure 1;

Figure 6 is a fragmentary sectional view taken substantially along line 6—6 of Figure 5;

Figure 7 is a fragmentary sectional view taken substantially along line 7—7 of Figure 1; and

Figure 8 is a fragmentary transverse sectional view taken substantially along line 8—8 of Figure 1.

In the drawings, the embodiment of my invention illustrated is shown as providing an articulated connection between a connecting trough 10 of a shaker conveyor trough line (not shown) and a rearwardly spaced connecting trough 11 of said trough line, to permit lateral swinging movement of one trough with respect to the other about a plurality of parallel spaced vertical axes, so the shaker conveyor may carry material around corners, or so a pick-up member extending from the forward end of the trough 10 may pick up material from the extreme corners of a wide room, or may be extended along a cross cut or entry at an angle to the main part of the conveyor, to pick up material therefrom. Said trough 11 may be connected to and driven from the shaker conveyor trough line, and is the driving trough of the articulated connection, while said trough 10 may have a driven trough connected thereto (not shown) and is the driven trough of the articulated connection.

The articulated connection herein shown operates on principles somewhat similar to those shown and described in Patent No. 2,330,946, which issued to E. R. Bergmann on Oct. 5, 1943, and includes a base 12 adapted to be held in position on the ground during operation of the conveyor by means of a plurality of jacks 13, 13, interposed between the mine roof and opposite sides of said base. A plate 14 overlies said base and is mounted thereon for yieldably restrained movement with respect thereto in a vertical direction and forms a supporting means for the moving parts of the articulated connection.

A relatively short intermediate trough 15 having outwardly flared curved forward and rear ends 16 and 17, respectively, is connected between the connecting troughs 10 and 11. Said connecting trough 10 has a curved discharge end, substantially conforming to the form of the curved forward end 16 of the intermediate trough 15, and is nested within said forward end of said trough so as to discharge material onto said trough when in various positions of articulation with respect thereto. The curved rear end 17 of said intermediate trough is nested within a

curved receiving end of the connecting trough 11. Said intermediate and connecting troughs thus provide a continuous closed trough for the passage of material therealong when said connecting trough 10 and said intermediate trough 15 are in various positions of articulation with respect to said connecting trough 11.

The intermediate trough 15 is connected adjacent its receiving and discharge ends to said connecting troughs 10 and 11 by means of bosses 22 and 23, respectively. The boss 22 is mounted in the bottom of the connecting trough 10 and depends therefrom (see Fig. 4). Said boss extends through and has bearing engagement with an annular bearing member 24, secured to and depending from the bottom of the forward end of the intermediate trough 15. A supporting frame 25 has a central upwardly projecting portion 26, recessed within the bearing member 24 and secured to the bottom of the boss 22 by cap screws 27, 27. Said supporting frame has outwardly facing slotted portions 29, 29 extending along its outer sides, which have bearing strips 30, 30 mounted therein and extending therealong. Said bearing strips are adapted to have engagement with flanged rollers 31, 31 mounted in the outer ends of the furcations of a bifurcated support and controlling frame 33, on vertical shafts 34, 34 and ball bearings 35, 35. The distance between the flanges of said flanged rollers is greater than the thickness of said bearing strips to permit vertical displacement of said supporting frame 25 with respect to said rollers, to take care of variations in angles of the connecting trough 10 and the troughing connected to and extending therefrom (not shown) with respect to the base 12. An outboard support 36 extending forwardly from said supporting frame and herein shown as being formed integrally therewith, is secured to and forms a support for the bottom of the connecting trough 10, adjacent its forward end.

The control frame 33 extends rearwardly of the rollers 31, 31 beneath the intermediate trough 15, and its rear portion rests on the plate 14. Said control frame is pivotally mounted on said plate for movement about a vertical axis, disposed centrally of said plate, on a vertical bearing boss 37, mounted on and projecting upwardly from said plate (see Figure 4). Said control frame also has a pair of laterally spaced brackets 38, 38 opening towards each other and extending upwardly therefrom. Each of said brackets has a supporting and guide roller 39 mounted thereon, on a vertical shaft 40 and ball bearings 41, 41. Said rollers have V-shaped engaging faces which are adapted to engage corresponding V-shaped recesses extending along bearing strips 43, 43, mounted on and extending along opposite sides of a rearwardly projecting portion 44 of the supporting frame 25, and forming an antifriction support for the rear portion of said frame.

The vertical shafts 40, 40 each have an eccentric upper end portion 45 mounted in the upper portion of the bracket 38, and an eccentric lower end portion 46 mounted in the lower portion of said bracket (see Figure 7). A threaded lower end of said shaft extends beneath said bracket and has a nut 47 threaded thereon. A pin 48 holds said nut from turning movement with respect to said shaft. Turning said nut in one direction will move the roller towards its associated bearing strip 43 and form a means to take care of wear of the recessed face of said bearing strip and the face of said roller. A locking member 49 in the form of an open end wrench is

adapted to engage the head of said nut, to hold said nut and shaft from movement. The outer end of said locking member has a cap screw 50 threaded therein, which extends through the bracket 38 so as to be accessible from the top of said bracket.

The boss 23 depends from and is mounted in the bottom of the intermediate trough 15 adjacent the rear end thereof. An annular bearing member 51 is secured to and depends from the bottom of the connecting trough 11, and is pivotally mounted on said boss. A retaining cap 53 is secured to the bottom of said boss as by cap screws 54, 54. Said cap extends along the bottom of the annular bearing member 51 and laterally therefrom and along the inner portion of a support frame 55, mounted on the outer periphery of said bearing member, and serves to hold said annular bearing member and support frame in position with respect to each other and with respect to said depending boss. Anti-friction supporting and guide rollers 57, 57, having V-shaped engaging faces, are mounted in bifurcated bracket portions 59, 59 of the support frame 55, and are adapted to engage recessed facing V-shaped guides 60, 60, extending along opposite sides of the plate 14. Said guides are mounted in channels 61, 61 extending along said floating plate 14 adjacent opposite sides thereof. Studs and nuts 62, 62 are provided to secure said guides to said channels and floating plate.

The rollers 57, 57 are mounted on shafts 63, 63 having opposite eccentric ends, and have suitable nuts threaded on and secured to their upper ends, to form a means for turning said shafts to take care of wear of said rollers 57, 57 and guides 60, 60, in much the same manner as the rollers 39, 39. Locking members 65, 65 are provided to engage said nuts and lock said shafts from turning movement (see Figures 6 and 7).

A centering means is provided to center the base 12 and plate 14 with respect to the stroke of the conveyor when initially setting up the conveyor, to prevent the rollers 57, 57 from coming out of engagement with the guides 60, 60 during reciprocation of the conveyor. Said centering means is operated by hinged bearing plates 66, 66 adapted to be engaged by the jacks 13, 13, when holding said base in position on the ground. Said hinged bearing plates are held in an upright position when the jacks 13, 13 are disengaged therefrom by means of springs 67, 67, and when in this position, the centering mechanism is in position to center said base. When said bearing plates are engaged by said jacks, they are pivoted downwardly into engagement with the base 12, and pivot the centering mechanism into an inoperative position. Said centering mechanism operates on principles similar to those shown and described in Patent No. 2,347,074, which issued to E. R. Bergmann on April 18, 1944, and is no part of my present invention so will not herein be shown or described further.

Referring now to the mounting for the plate 14 on the base 12, a longitudinal shaft 70 is mounted adjacent one side of the base 12 in spaced support brackets 71, 71a, mounted on the top surface of said base and projecting upwardly therefrom a slight distance. Said shaft forms a pivotal mounting for the bearing plate 66 which is on the right-hand side of the machine when looking towards the trough 11, and also forms a pivotal mounting for the plate 14 on bracket members 72, 72a extending outwardly from said plate 14. The side of said plate opposite from

said shaft is engaged at its top by a pair of longitudinally spaced compression springs 73, 73, which yieldably restrain upward movement of said floating base about the axis of said shaft 70. As herein shown, said spring encircles a sleeve 74 extending through an apertured portion of said plate, and is abutted at its upper end by a washer 75 mounted on a bolt 76 extending through said sleeve. A nut 77 threaded on the upper end of said bolt holds said washer in position on said sleeve. The lower portion of said sleeve is flanged and has the bottom of said plate resting thereon. Said sleeve has a downwardly projecting annular portion 78, which extends through an apertured portion of the base 12 and may be secured to said base in a suitable manner, as by welding. Sufficient clearance is provided between said sleeves and the apertured portions of said plate to permit pivotal movement of said plate against the springs 73, 73, so that flexing of the base 12 will not flex said plate.

It may be seen from the foregoing that when the jacks 13, 13 are set on the hinged bearing plates 66, 66 and pivot said plates to rest on the top of the base 12, as in Figure 1, that they may be tightened between said base and the mine roof, to hold said base from movement with respect to the ground, and that where the ground is uneven, said jacks may exert sufficient pressure on opposite sides of said base to bend it to conform to the ground without bending the plate 14, said plate pivoting about the longitudinal shaft 70 against the springs 73, 73, to adapt it to substantially the plane of the shaker conveyor trough line.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. An articulated connection for a shaker conveyor trough line including a base, a plurality of jacks adapted to be interposed between a mine roof and opposite sides of said base, for holding said base stationary on a mine bottom, a plurality of troughs mounted on said base for reciprocable movement with respect thereto and so one may be moved laterally with respect to the other, and a plate overlying said base and forming a support means for said troughs and the articulated supporting mechanism therefor, and a mounting for said plate on said base, connecting said plate to said base for restrained movement with respect to said base in a vertical direction, so as to relieve said plate from the bending strains imparted to said base by means of said jacks and to prevent binding of said troughs and the supporting means therefor, when said base is distorted by jacking down on an uneven mine bottom.

2. An articulated connection for a shaker conveyor trough line including a base, a plurality of jacks adapted to be interposed between a mine roof and opposite sides of said base, for holding said base stationary on a mine bottom, a plurality of troughs mounted on said base for reciprocable movement with respect thereto and so one may be moved laterally with respect to the other, a plate overlying said base and forming a support means for said troughs and the articu-

lated supporting mechanism therefor, a mounting for said plate on said base connecting said plate to said base for restrained movement with respect to said base in a vertical direction so as to relieve said plate from the bending strains imparted to said base by means of said jacks, to prevent binding of said troughs and the supporting means therefor when said base is bent by jacking down on an uneven mine bottom; and the connection between said base and plate including a pivotal mounting for one side of said plate on said base, and yieldable means engaging the opposite side of said plate.

3. An articulated connection for a shaker conveyor trough line including a base, a plurality of jacks adapted to be interposed between a mine roof and opposite sides of said base, for holding said base stationary on a mine bottom, a plurality of troughs mounted on said base for reciprocable movement with respect thereto and so one may be moved laterally with respect to the other, a plate overlying said base and forming a support means for said troughs and the means for supporting said troughs for reciprocable and lateral movement with respect to said base, a mounting for said plate on said base connecting said plate to said base for restrained movement with respect to said base so as to relieve said plate from the bending strains imparted to said base by said jacks, to prevent binding of said troughs and the supporting means therefor when said base is distorted by jacking down on an uneven mine bottom, and the connection between said base and said plate including a shaft mounted on said stationary base adjacent one end thereof and extending longitudinally of the conveyor trough line and forming a pivotal mounting for said plate, and yieldable means connected between said base and said plate for yieldably restraining vertical movement of said plate.

4. An articulated connection for a shaker conveyor trough line including a base, a plurality of jacks adapted to be interposed between a mine roof and opposite sides of said base, for holding said base stationary on a mine bottom, a plurality of troughs mounted on said base for reciprocable movement with respect thereto and so one may be moved laterally with respect to the other, a plate overlying said base and forming a support means for said troughs and the means for supporting said troughs for reciprocable and lateral movement with respect to said base, a mounting for said plate on said base connecting said plate to said base for restrained movement with respect to said base so as to relieve said plate from the bending strains imparted to said base by said jacks, to prevent binding of said troughs and the supporting means therefor when said base is distorted by jacking down on an uneven mine bottom, and the connection between said base and said plate including a shaft mounted on said base adjacent one side thereof and extending longitudinally of the conveyor trough line and forming a pivotal mounting for said plate, and spring means connected between said base and the side of said plate opposite from said shaft, for yieldably restraining movement of said plate in an upward direction.

5. In an articulated connection for a shaker conveyor trough line, a base, a plurality of jacks adapted to be interposed between the mine roof and said base, for holding said base stationary on the mine bottom, a driving trough and a driven trough, and means for mounting said troughs on said base for reciprocable move-

ment with respect thereto and so one may be moved laterally with respect to the other, including a plate extending over and mounted on said base for restrained movement with respect thereto in a vertical direction about one side of said base, so as to avoid binding of the operating parts of said articulated connection when said first mentioned base is distorted by the pressure exerted on opposite sides thereof by said jacks, when on an uneven mine bottom.

6. In an articulated connection for a shaker conveyor trough line, a base, a plurality of jacks adapted to be interposed between the mine roof and said base, for holding said base stationary on the mine bottom, a driving trough and a driven trough, and means for mounting said troughs on said base for reciprocable movement with respect thereto and so one may be moved laterally with respect to the other, including a plate extending over and mounted on said base for restrained pivotal movement with respect thereto in a vertical direction about an axis extending longitudinally of the conveyor trough line and along one side of said base, so as to avoid binding of the operative parts of said articulated connection, when said base is distorted by pressure exerted on opposite sides thereof by said jacks, when resting on an uneven mine bottom.

7. In an articulated connection for a shaker conveyor trough line, a base, a plurality of jacks adapted to be interposed between the mine roof and bottom, for holding said base stationary on the mine bottom, a driving trough and a driven trough, and means for mounting said troughs on said base for reciprocable movement with respect thereto and so one may be moved laterally with respect to the other, including a plate extending over and mounted on said base for restrained movement with respect thereto in a vertical direction about one of its sides and about an axis extending longitudinally of the conveyor trough line, so as to avoid binding of the operative parts of said articulated connection, when said base is distorted by the pressure exerted on opposite sides thereof by said jacks, when resting on an uneven mine bottom.

8. In an articulated connection for a shaker conveyor trough line, a base, a plurality of jacks adapted to be interposed between the mine roof and bottom, for holding said base stationary on the mine bottom, a driving trough and a driven trough, and means for mounting said troughs on said base for reciprocable movement with respect thereto and so one may be moved laterally with respect to the other, including a plate extending over and mounted on said base for restrained movement with respect thereto in a vertical direction about one of its sides and about an axis extending longitudinally of the conveyor trough line so as to avoid binding of the operative parts of said articulated connection when said first mentioned base is distorted by the pressure exerted on opposite sides thereof by said jacks, when resting on an uneven mine bottom, and yieldable means connected between said base and said plate and yieldably restraining upward movement of said plate with respect to said base.
9. In an articulated connection for a shaker conveyor trough line, a base, a plurality of jacks adapted to be interposed between the mine roof and bottom for holding said base stationary on the mine bottom, a driving trough and a driven trough and means for mounting said troughs on said base for reciprocable movement with respect thereto and so one may be moved laterally with respect to the other, including a plate mounted on and extending over said base, a shaft mounted on said base and extending along one side thereof in the general direction of the conveyor trough line and having said plate mounted thereon for movement about the axis of said shaft, and spring means connected with said base and engaging the top of said plate to yieldably restrain movement thereof in a vertical direction, to permit said base to be bent by being held in position on an uneven mine bottom by means of said jacks engaging opposite sides thereof, without bending said plate and the parts mounted thereon.

WILLIAM W. SLOANE.
